FLASHER TYPE TRAFFIC SIGNAL

Daniel D. Grissinger, Wellington, Ohio, assignor
to Cleveland Steel Products Corporation, Cleve-
land, Ohio, a corporation of Ohio

Application July 14, 1950, Serial No. 173,781

8 Claims. (Cl. 177—327)

1

This invention relates to flasher type traffic signals adapted to be used for directing attention to highway obstructions, such as safety zones, bridge pillars, and the like, or to be used in connection with roadside signs, such as stop and speed limit signs, and caution signals at road intersections, and for other analogous purposes.

A principal object of the invention is to provide an improved, dual, electric, blinker light assembly of such a character that the light sources and light interrupting mechanism can be electrically disconnected in one operation and removed from their housing as a unit for service or for interchanging complete units.

Another principal object of the invention is to provide a new and improved mechanism for causing a pair of spaced signal lights to flash on and off alternately.

Further objects of the invention are to provide a light interrupting mechanism in which the light transmitted through an aperture or lens is cut off by interposing light obstructing vanes between the light source and the aperture or lens from opposite sides simultaneously; to provide a single mechanism for alternately cutting off the light so transmitted from two spaced sources through separate apertures or lenses; and to provide a single mechanism for accomplishing these objectives in such a manner that the speed of movement of the vanes over the light paths may be varied within limits, with respect to the period of flashing of the lights while driving the mechanism as a whole at a constant speed.

Still another object of the invention is to provide a dual electric blinker light assembly of the character described in which the edges of the vanes moving across the light paths are not distinctly visible so that the effect simulates what would be achieved by actually making and breaking the electrical circuit to the light sources.

A characteristic feature of the invention is the provision of an operating unit comprising a frame, light sources mounted on the frame, and power operated means for interrupting or blocking light transmitted from the light sources, the entire operating unit being slidably receivable in and removable from a suitable housing with appropriately located light transmitting apertures formed therein.

Another characteristic feature of the invention is the employment of a pair of oppositely oscillating vanes that cooperate in alternately blocking the transmission of light transmitted from a plurality of light sources through individual apertures in the housing.

Still another characteristic feature of the invention is the employment of special lenses across the light transmitting openings of the housing, the lenses having surface projections or depre-

sions shaped to distort light rays passing therethrough, thereby making the edges of the light obstructing vanes visually indistinct.

The foregoing and still other objects and features of the invention will be better understood by reference to the accompanying drawings and the following description of an illustrative embodiment of the invention. Referring to the several views of the drawing—

Figure 1 is a front elevation of a signal housing with some of the enclosed mechanism shown in dotted lines;

Fig. 2 is a fragmentary side elevation of the device shown in Fig. 1;

Fig. 3 is a plan view of the device shown in Fig. 1, with a portion of the cover of the housing broken away to show more clearly a portion of the apparatus contained therein;

Fig. 4 is a horizontal section through the device shown in Fig. 1, the plane of the section being indicated by the line 4—4 in Fig. 1;

Fig. 5 is an elevational view similar to Fig. 1 but on a reduced scale, showing the signal housing with a traffic sign mounted thereon;

Fig. 6 is an elevational view of the back side of a removable operating unit contained in the housing of the device of Fig. 1 and carrying all of the essential operating parts of the device; and

Fig. 7 is a vertical section through the unit shown in Fig. 6, the plane of the section being indicated by the line 7—7 in Fig. 6, and a portion of the bottom of the housing in which the unit is mounted being indicated in phantom outline.

Referring to the drawings in detail, the embodiment of the invention shown therein involves a signal housing that may suitably be constructed of sheet metal panels, including a pair of identical side panels 11, a back panel 12, and a front panel 13. As best shown in Fig. 4, the side panels

may be in the form of channel members, and the front and back panels may have their side edges folded around the flanges of the channel shaped side panels to form the four sides of a housing of generally rectangular cross section. The bottom of the housing may comprise a flanged casting 14 having its flanges bolted to the side panels 11 adjacent their lower edges. A removable sheet metal cover 16 for the housing may be conveniently mounted thereon by providing it with an upturned flange 17 adapted to fit under a downturned flange 18 on the upper edge of the front panel 13. The cover 16 is preferably formed with downturned side flanges 19 and a downturned end flange 20 that are welded together at their ends to form a continuous rim surrounding three sides of the upper end of the housing and spaced laterally therefrom to permit air circulation through upper vent openings 25a (Fig. 2) in the

housing. The cover may be conveniently locked in its closed position by means of a hasp 21 hinged to the end flange 20 of the cover and slotted to receive a staple 22 mounted on the back panel 12 of the housing, whereby the cover may be locked in place in a well known manner by a padlock or the like (not shown), and may be unlocked and removed by swinging it upwardly while moving it rearwardly.

The above described housing is adapted to be mounted on a threaded upper end of a suitable post 23 by means of an internally threaded boss 24 on the casting 14. Suitable openings 25b in the casting 14 cooperate with the upper vent openings 25a in permitting air to circulate through the housing. These openings are preferably all covered by suitable screening (not shown).

Inside the housing a pair of channel shaped guide members 26 may be secured to the side panels 11, as by welding, for slideably receiving an operating unit, including a frame carrying a pair of electrically energized light sources and a motor driven light interrupting mechanism. With this arrangement the entire operating unit may be slid into place in the housing and readily removed at will to facilitate the repair or replacement of its parts or for the substitution of a replacement unit.

The frame of the operating unit may conveniently comprise a channel shaped main panel 31 having its flanged side edges slideably receivable in the channel shaped guide members 26 of the housing. This panel serves as a light shield and also as the principal frame member of the above mentioned operating unit.

The panel 31 is provided with an upper light transmitting aperture 32 and a lower light transmitting aperture 33, and cylindrical light shields 34 and 35 are preferably secured to one side of panel 31 around the light transmitting apertures 32 and 33 respectively. On the opposite side of panel 31, approximately at the center of the panel, a U-shaped bracket 37 is secured to the panel in any convenient manner, as by bolts 38, for mounting a light interrupting mechanism, hereinafter described, and also for mounting a bracket 39 carrying a light socket 40 that is adapted to receive a conventional electric light bulb 41. The socket supporting bracket 39 may be welded to the U-shaped bracket 37, and the socket 40 is preferably mounted on the bracket 39 by means of bolts 42 or the like. The bracket 39 is designed to support the socket 40 and light bulb 41 so that the brightest portion of the bulb filament is positioned substantially on the axis of the upper light transmitting aperture 32 for transmitting a beam of light of maximum brilliance through this light transmitting aperture.

A lower electric light bulb 43 and socket 44 are similarly mounted on a bracket 46, which may be welded directly to the panel 31. This lower bracket 46 is located so as to maintain the same relationship between the lower bulb 43 and lower light transmitting aperture 33 as the relationship between the upper light bulb 41 and upper light transmitting aperture 32.

The above mentioned light interrupting mechanism includes a pair of substantially complementary, elongated blades or vanes 51 and 52. These blades are pivotally mounted substantially midway between their ends on pivot shafts 53 and 54, respectively, for free oscillation thereon. Each blade is provided with an elongated bearing 55 that may conveniently be made of a length

of tubing welded at one end to the blade with which it is associated.

The pivot shafts 53 and 54 are preferably mounted at one end in a plate 56 in any suitable manner, as by welding, and project through the bearings 55 and through aligned apertures in the U-shaped bracket 37. The plate 56 is preferably of sufficient length so that its opposite ends may be disposed between the panel 31 and the ends of the U-shaped bracket 37, whereby the bracket and plate may both be secured to the panel 31 by means of bolts 38.

Each of the blades 51 and 52 comprises a pair of arms that extend generally in opposite directions from its pivot shaft but are disposed so that they diverge slightly outwardly from a straight line, as best shown in Fig. 6. The outer edges of the blades may be provided with a stiffening flange 57 and the inner edges of the blades are preferably formed adjacent their ends with laterally projecting flange portions 58 and 59. One of the flange portions 58 of each blade lies in the plane of the body of the blade, and the other flange portion 59 at the opposite end of the blade is slightly offset so that the flange portion 59 of one blade may overlap the flange portion 58 of the other blade as the two blades are oscillated in opposite directions about their respective pivot shafts. Thus, as the upper ends of the two blades are brought together with the flange portion 59 of one of the blades overlapping the flange portion 58 of the other, a light blocking shield is formed between the upper light bulb 41 and the upper light transmitting aperture 32, thereby completely cutting off the transmission of light from the upper light bulb through the upper light transmitting aperture. Similarly, when the lower ends of the two blades are brought together they block the transmission of light from the lower light bulb 43 through the lower light transmitting aperture 33.

The configurations of the blades and the location of their centers of oscillation are such that the center of gravity of each blade is disposed laterally outwardly of its axis. Thus, referring to Fig. 6, the left hand blade 51 is urged by gravity in a counter-clockwise direction and the right hand blade 52 is urged by gravity in a clockwise direction for bringing the lower ends of the two blades together.

Oscillation of the blades about their axes is effected by means of a pair of cams 61 and 62 that are rotatably mounted on the shaft 63 of a synchronous electric motor 64. The motor 64 may be mounted on the panel 31 below the blade pivot shafts 53 and 54 by means of a U-shaped bracket 66 secured at its opposite ends to the panel 31 by means of bolts 67. The motor may be secured to the U-shaped bracket 66 in any suitable manner, as by bolts 68, passing through lugs formed on the motor housing and through the body of the U-shaped bracket 66. The blades 51 and 52 are provided with respective cam engaging flanges 71 and 72 that may conveniently be formed of sheet metal and welded to the respective blades. During a portion of their rotation with the motor shaft 63, the cams 61 and 62 respectively push against the flanges 71 and 72 and urge the lower ends of the blades 51 and 52 in opposite directions. This causes the blades to rotate about their axes in opposite directions against the force of gravity for bringing the upper ends of the blades together between the upper light bulb 41 and the upper light transmitting aperture 32. During the remainder of

their rotation, the cams 61 and 62 permit the lower ends of the blades to be swung together, by gravity, between the lower light bulb 43 and the lower light transmitting aperture 32. Thus, during each revolution of the motor shaft, the passage of light through the light transmitting apertures 31 and 32 is blocked at one aperture and restored at the other, and then restored at the first and blocked at the second.

The front panel 13 of the signal housing is provided with upper and lower light transmitting apertures 76 and 77 that are respectively aligned with the upper and lower apertures 31 and 32 in the main panel 31 of the above described operating unit. These apertures 76 and 77 in the front panel 13 are preferably provided with lens supporting frames 78 in which suitable, clear or colored, light transmitting lenses 79 may be secured by means of snap rings 81 in a well known manner.

The lenses 79 are preferably formed with a multiplicity of surface projections on at least one face thereof, such as the ribs 82 shown on the outer face of the lenses in Figures 1, 3 and 4. Instead of parallel, rib-shaped, surface projections, the lenses may be provided with any other desired form of surface projections adapted to diffuse the light passing therethrough sufficiently to render the outline of the light obstructing blades indistinct when viewed through the lenses from the outside of the signal housing. The effect of the resulting light diffusion is such that the bulbs appear to be actually turned off as the blades close between the bulbs and their respective light transmitting apertures 31 and 32. This effect is enhanced by the fact that the light is obstructed simultaneously from two sides of the light transmitting apertures by the closing of the blades.

From the foregoing description of the light obstructing or light interrupting mechanism, it will be appreciated that as the blades 51 and 52 are oscillated about their axes by the action of the cams 61 and 62, the light transmitted through the upper and lower lenses 79 will be momentarily interrupted alternately at regular intervals. It will also be apparent that the speed with which the ends of the blades move together for interrupting the light transmitted from the bulbs through the lenses is determined in part by the speed of the motor 64 and in part by the contour of the cams 61 and 62, whereas the intervals between successive light interruptions are determined solely by the speed of the motor 64. Thus, by a proper selection of cam contours the speed at which the ends of the blades are brought together for extinguishing the lights may be varied within limits without altering the motor speed.

To keep to a minimum the number of operations required for removing the operating unit from the housing, the electrical current supply to the light bulbs and to the motor is carried by a single circuit in which the light bulbs and the motor are connected in parallel. Thus, a single pair of electrical conductors 86 and 87 may respectively extend from a conventional male plug 88 to terminals 86a and 87a of the upper light socket 40 and thence to terminals 86b and 87b of the motor 64 and thence to terminals 86c and 87c of the lower light socket 44, as shown in Fig. 6. A conventional female socket 89, to which the required electrical power is transmitted by a double cable 91, may be mounted on one of the side panels 11 of the housing by bolts 92. Thus, when a single connection is made between

the plug 88 and the socket 89, both the light bulbs and the motor are connected to the source of electrical power. When it is desired to remove the operating unit for repair or replacement of parts or for substituting an entire new unit, it is merely necessary to remove the housing cover 16, disengage the plug 88 from the socket 89, and lift the entire unit upwardly out of the housing. The unit may thereafter be replaced, or a new unit inserted, by reversing this series of three simple operations.

The simplicity of the light interrupting mechanism forming a part of the present invention is such that it may be economically manufactured, installed, and serviced. The design of the mechanism is also such that it is subject to a minimum of wear in use and, therefore, is adapted to run for long periods of time without attention or service of any kind. While, for simplicity, the bearings 55 are shown and described herein as simple bushings turning on the fixed shafts 53 and 54, it will be apparent that the life of the mechanism may readily be even further extended by the employment of any of the well known types of permanently lubricated bearings for pivotally mounting the light interrupting blades on the pivot shafts 53 and 54.

In operation a blinker signal constructed in accordance with the present invention conforms to the most rigid standards regarding the abruptness with which the light beams transmitted through the lenses are cut on and off, and also meets the most rigid standards of dependability in service.

While the invention has been illustrated with reference to a specific embodiment thereof, it will be obvious that the details disclosed are susceptible to considerable modification without departing from the true spirit and scope of the invention as defined in the appended claims.

Having described my invention in detail, I claim:

1. A flashing traffic signal comprising a stationary frame including a vertically disposed, light-shielding panel, upper and lower light transmitting apertures through said panel, upper and lower light sources respectively mounted on said frame on one side of said panel and in alignment with said apertures for directing light therethrough, oscillating means mounted on said frame between said light sources and said panel for alternately and momentarily blocking the passage of light from said light sources through said apertures, said oscillating means comprising a pair of cooperating, elongated, blades pivotally mounted for oscillation about their longitudinal centers, and means for oscillating said blades so that they sweep over substantially contiguous upper areas between said upper light source and upper light transmitting aperture and over substantially contiguous lower areas between said lower light source and lower light transmitting aperture.

2. In a flashing traffic signal comprising a stationary frame including a vertically disposed, light-shielding panel, upper and lower light transmitting apertures through said panel, upper and lower light sources respectively mounted on said frame on one side of said panel and in alignment with said apertures for directing light therethrough; the combination of a pair of cooperating, generally complementary, elongated blades disposed side by side between said light sources and said panel and pivotally mounted substantially midway between their ends for co-

ordinated oscillation parallel to said panel, and means for oscillating said blades through angles selected so that the blades sweep over substantially contiguous upper areas between said upper light source and upper light transmitting aperture and over substantially contiguous lower areas between said lower light source and lower light transmitting aperture.

3. In a flashing traffic signal comprising a stationary frame including a vertically disposed, light-shielding panel, upper and lower light transmitting apertures through said panel, upper and lower light sources respectively mounted on said frame on one side of said panel and in alignment with said apertures for directing light therethrough; the combination of a pair of cooperating, generally complementary, elongated blades disposed side by side between said light sources and said panel and pivotally mounted substantially midway between their ends for co-ordinated oscillation parallel to said panel, and means for oscillating said blades through angles selected so that the blades sweep over substantially contiguous upper areas between said upper light source and upper light transmitting aperture and over substantially contiguous lower areas between said lower light source and lower light-transmitting aperture, the centers of gravity of said blades being spaced from the axes of oscillation of the blades in locations selected so they are normally urged by gravity to rotate in opposite directions.

4. In a flashing traffic signal comprising a stationary frame including a vertically disposed, light-shielding panel, upper and lower light transmitting apertures through said panel, upper and lower light sources respectively mounted on said frame on one side of said panel and in alignment with said apertures for directing light therethrough; the combination of a pair of cooperating, generally complementary, elongated blades disposed side by side between said light sources and said panel and pivotally mounted substantially midway between their ends for co-ordinated oscillation parallel to said panel, and means for oscillating said blades through angles selected so that the blades sweep over substantially contiguous upper areas between said upper light source and upper light transmitting aperture and over substantially contiguous lower areas between said lower light source and lower light transmitting aperture, the centers of gravity of said blades being located transversely outwardly in opposite directions from the axes of oscillation of the blades, whereby they are normally urged by gravity to rotate in opposite directions, and said means for oscillating said blades acting against opposed surfaces thereof for intermittently rotating them in opposite directions against the force of gravity.

5. In a flashing traffic signal comprising a stationary frame including a vertically disposed, light-shielding panel, upper and lower light transmitting apertures through said panel, upper and lower light sources respectively mounted on said frame on one side of said panel and in alignment with said apertures for directing light therethrough; the combination of a pair of cooperating, generally complementary, elongated blades disposed side by side between said light sources and said panel and pivotally mounted adjacent their centers for coordinated oscillation parallel to said panel, and means for oscillating said blades through angles selected so that the blades sweep over substantially contiguous upper

areas between said upper light source and upper light-transmitting aperture and over substantially contiguous lower areas between said lower light source and lower light transmitting aperture, the centers of gravity of said blades being spaced from the axes of oscillation of the blades in locations selected so they are normally urged by gravity to rotate in opposite directions, and said means for oscillating said blades comprising rotating cam means disposed between adjacent edges of the blades and engaging opposed surfaces thereon for intermittently rotating them in opposite directions against the force of gravity.

6. In a flashing traffic signal including a frame and spaced light sources mounted on said frame, the combination of a pair of cooperating elongated light obstructing blades having their opposite ends respectively disposed adjacent said spaced light sources, said blades being pivotally mounted on said frame adjacent their longitudinal mid-portions for oscillation through angles selected so that the ends of the blades adjacent each light source sweep over substantially contiguous areas, and means for oscillating said blades in timed relation so that their directions of rotation are opposite at any stage in their cycle of operation.

7. A flashing light signal comprising a housing having spaced light transmitting apertures in one wall thereof, an operating unit slidably receivable in said housing and slidably removable therefrom, said operating unit including a frame, spaced electric light sources mounted on said frame for disposition opposite said apertures in said housing, oscillating means mounted on said frame for disposition between said light sources and said apertures, said oscillating means being operative for alternately and momentarily blocking the passage of light from said light sources through said apertures, and an electric motor mounted on said frame for driving said oscillating means.

8. A flashing light signal comprising a housing having spaced light transmitting apertures in one wall thereof, an operating unit slidably receivable into an operative position in said housing and slidably removable therefrom, said operating unit including a frame, spaced electric light sources mounted on said frame for operative disposition opposite said apertures in said housing, oscillating means mounted on said frame for operative disposition between said light sources and said apertures, said oscillating means being operative for alternately and momentarily blocking the passage of light from said light sources through said apertures, an electric motor mounted on said frame for driving said oscillating means, a pair of electrical terminals mounted on said housing, a pair of electric wires connecting said electric light sources and said motor in parallel, and means for detachably connecting said pair of wires to said pair of terminals for permitting substitution of interchangeable operating units.
